CLAIM

The ornamental design for a bottle as shown and described.

DESCRIPTION

FIG. 1 is a perspective view of a bottle;

FIG. 2 is a front view of the bottle shown in FIG. 1;

FIG. 3 is a right side view of the bottle shown in FIG. 1;

FIG. 4 is a rear view of the bottle shown in FIG. 1;

FIG. 5 is a left side view of the bottle shown in FIG. 1;

FIG. 6 is a top view of the bottle shown in FIG. 1; and,

FIG. 7 is a bottom view of the bottle shown in FIG. 1.

The part represented by the solid line is the portion for which design registration is sought as a partial design. The chain dotted line only indicates the boundary between the portion for which design registration is sought as part design and the other portions.

The broken lines shown in the drawings depict portions of the bottle that form no part of the claimed design.
